US00D879067S

(12) **United States Design Patent** (10) **Patent No.:** **US D879,067 S**
Hu (45) **Date of Patent:** **** Mar. 24, 2020**

(54) **EARPHONES**

(71) Applicant: **SHENZHEN HONGLIAN INDUSTRIAL CO., LTD.**, Shenzhen (CN)

(72) Inventor: **Dechen Hu**, Shenzhen (CN)

(73) Assignee: **SHENZHEN HONGLIAN INDUSTRIAL CO., LTD.**, Shenzhen (CN)

(**) Term: **15 Years**

(21) Appl. No.: **29/714,076**

(22) Filed: **Nov. 21, 2019**

(51) LOC (12) Cl. **14-01**

(52) U.S. Cl.

USPC **D14/205; D14/223**

(58) **Field of Classification Search**

USPC D14/205, 223; D24/174; 128/864, 865, 128/866; 181/129, 130, 135; 379/430, 379/431; 381/380, 381, 370, 374; 455/90.3, 575.1, 569.1

CPC H04R 1/10; H04R 1/1033; H04R 1/105; H04R 1/1066; H04R 1/1016; H04R 5/033; H04R 5/0335; H04R 1/1091; H04R 1/1083; H04R 25/00; B44F 3/00

See application file for complete search history.

Primary Examiner — Paula Allen Greene

(57) **CLAIM**

The ornamental design for earphones, as shown and described.

DESCRIPTION

FIG. 1 is a perspective view of earphones showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and, FIG. 10 is an enlarged view of portion 10 shown in FIG. 2. The broken lines in the drawings depict portions of the earphones that form no part of the claimed design.

1 Claim, 10 Drawing Sheets
